UNITED STATES PATENT OFFICE.

CHARLES F. SMITH, OF NEW BRITAIN, CONNECTICUT, ASSIGNOR TO THE
LANDERS, FRARY & CLARK, OF SAME PLACE.

DESIGN FOR A KNIFE BLADE AND BOLSTER.

SPECIFICATION forming part of Design No. 33,682, dated December 11, 1900.

Application filed April 26, 1900. Serial No. 14,508. Term of patent 7 years.

To all whom it may concern:

Be it known that I, CHARLES F. SMITH, a citizen of the United States, residing at New Britain, in the county of Hartford and State of Connecticut, have invented and produced a new and original Design for Knife Blades and Bolsters, of which the following is a specification, reference being had to the accompanying drawing, forming part thereof.

10 The only figure of the drawing is a side elevation of a knife blade and bolster, showing my design.

As shown in the drawing, the contour of the blade in side view is somewhat in the shape 15 of a simitar, although it is the broadest near the butt-end. An ordinary tang 8 is indicated by broken lines, the longitudinal direction of the said tang indicating the direction of the longitudinal center of the blade. Adjacent to the tang is an ordinary bolster 7, with a rounded groove or neck, and between the said bolster and the blade is an intermediate portion 6 of a unique form and which aids 20 in giving a striking appearance to the complete design. This intermediate portion 6 has flat sides in continuation of the flat sides 25 of the blade, and its upper edge extends straight forward for a short distance parallel to the longitudinal center of the blade and then curves upwardly and meets the back of 30 the blade with a rounded corner, which merges into the beveled upper face 5, that extends the entire length of the blade at the back 2. The lower edge of the intermediate portion 6 35 also extends forwardly parallel to the longitudinal center of the blade and then downwardly with a convex turn, and from the convex turn it extends straight down to the heel

on a line nearly at right angles to the longitudinal center of the blade. The downward extension from the intermediate portion 6 to the heel of the blade is materially in excess of its upward extension to the back, as shown.

As before stated, the contour of the blade in side view is somewhat simitar-shaped and 45 somewhat resembles the contour of the blade in my prior design, No. 24,163, patented April 2, 1895, but differs therefrom, in addition to the form of the intermediate portion, by having its edge 3 extend forward from the 50 heel in a straight line parallel to the longitudinal center of the blade without any drop for more than one-third of the length of the blade and then extending to the point or tip 4 by an upwardly-convex curve, also, in that 55 the back of the blade extends forwardly from the rounded corner at its junction with the intermediate portion 6 on a straight line parallel to the longitudinal center of the blade for about one-eighth of its length and then in 60 a concave form to the point or tip 4.

The differences in the contour of the blade over my prior design, in connection with the bevel 5, extending the whole length of the back, and the novel intermediate portion 6, 65 are all combined in one harmonious unitary design, as shown.

Having described my invention, what I claim as new, and desire to secure by Letters Patent, is—

The design for a knife blade and bolster, as herein shown and described.

CHARLES F. SMITH.
